Application September 23, 1953, Serial No. 26,919

Term of patent 14 years

(Cl. D40—1)

To all whom it may concern:

Be it known that we, Harold D. Gabbert, a citizen of the United States and a resident of Houston, in the county of Harris and State of Texas, and Robert L. Williams, a citizen of the United States and a resident of Houston, in the county of Harris and State of Texas, and Furman H. Tyner, a citizen of the United States and a resident of Houston, in the county of Harris and State of Texas, have invented a new, original, and ornamental Design for an Electric Lawn Edger, of which the following is a specification, reference being had to the accompanying drawings forming a part hereof.

Referring to the drawings:

Fig. 1 is a front elevational view of an electric lawn edger embodying our new design.

Fig. 2 is a side elevational view taken from the right side of Fig. 1.

Fig. 3 is a side elevational view taken from the left side of Fig. 1.

Fig. 4 is a perspective view showing the rear and top of the edger.

The dominant features of the design are shown in full lines.

We claim:

The ornamental design for an electric lawn edger, as shown and described.
